(57) CLAIM

The ornamental design for the waste receptacle, as shown and described.

DESCRIPTION

FIG. 1 is a perspective view of a waste receptacle according to the present invention;

FIG. 2 is a front elevation view of FIG. 1;

FIG. 3 is a rear elevation view of FIG. 1;

FIG. 4 is a left side view of FIG. 1;

FIG. 5 is a right side view of FIG. 1;

FIG. 6 is a top plan view of FIG. 1; and,

FIG. 7 is a bottom view of FIG. 1.

The broken lines shown in the figures are included for the purpose of illustrating portions of the waste receptacle and form no part of the claimed design.
